UNITED STATES PATENT OFFICE.

GEORGE H. GILMAN AND HENRY M. ROBERTSON, OF ST. PAUL, MINNESOTA.

DRAFT-RIGGING.

1,073,578.

Specification of Letters Patent. Patented Sept. 16, 1913.

Application filed December 21, 1911. Serial No. 697,196.

To all whom it may concern:

Be it known that we, GEORGE H. GILMAN and HENRY M. ROBERTSON, citizens of the United States, residing at St. Paul, in the 5 county of Ramsey and State of Minnesota, have invented certain new and useful Improvements in Draft-Rigging; and we do hereby declare the following to be a full, clear, and exact description of the invention, 10 such as will enable others skilled in the art to which it appertains to make and use the same.

Our invention relates to draft rigging for cars, and has for its object to provide a simple and efficient auxiliary or safety draft connection or attachment therefor.

To the above ends, generally stated, the invention consists of the novel devices and combinations of devices hereinafter described and defined in the claims.

In the standard Master Car Builders' type of draft rigging, the coupler draft bar is, as is well known, provided with a draft yoke or stirrup secured thereto usually by heavy 25 rivets.

One of the great causes of accidents and of the disablement of cars is the tearing loose of the draft yoke or stirrup due, sometimes, to the breaking of the said draft yoke or stirrup but more frequently to shearing of the rivets which secure it to the coupler draft bar.

Our invention provides an auxiliary device which prevents the coupler draft bar from being torn loose when the draft yoke is broken or disabled, as stated.

The invention, in its preferred form, is illustrated in the accompanying drawings wherein like characters indicate like parts 40 throughout the several views.

Referring to the drawings: Figure 1 is a view chiefly in vertical section, but with some parts in full elevation and with some parts broken away showing our invention 45 incorporated in or used in connection with a draft rigging of the Master Car Builders' type; Fig. 2 is a view partly in plan and partly in horizontal section, and with some parts broken away, showing the draft rigging illustrated in Fig. 1, the platform of 50 the car being removed; and Fig. 3 is a perspective view showing portions of the draft rigging.

Of the parts of the car structure, the numeral 1 indicates the car platform, and the 55 numeral 2 the draft sills.

The numeral 3 indicates standard coupler having a shank or draft bar 4 to which the usual draft yoke 5 is shown as secured by the customary rivets 6.

The numeral 7 indicates draft plates of the usual or any suitable construction which are set into and rigidly secured to the sills 2, and are provided with front and rear draft lugs 8 that coöperate with the customary 65 front and rear followers 9. The usual springs or compressing resisting members 10 are interposed between the followers 9.

In accordance with the invention, one of the followers, preferably the front follower, 70 is provided with forwardly projecting arms 11 that embrace the sides of the coupler draft bar or shank 4 and are provided with elongated slots 12. The draft bar or shank 4 is provided with projections, preferably 75 afforded by transversely extended horizontal key 13 and the ends of which project through and work in the said slots 12.

The slots 12 are of such length that under movements imparted to the draft bar 4 by 80 ordinary bumping and draft strains, the keys or lugs 13 will move freely in the slots 12 of the arms 11 and the draft bar and yoke will be permitted to operate in the customary way upon the spring pressed follower 85 9. If, however, the yoke or stirrup 5 be torn loose from the draft bar, the lugs 13 under draft strains will move to the front end extremities of the slots 12, and will then hold the said draft bar operatively coupled 90 to the front follower 9 and through the latter to the front draft lugs 8 so that the draft rigging is still operative. In this contingency, the draft rigging under bumping 95 strains will operate just as it does when the draft yoke is operatively connected because, as is well known, under bumping strains the draft bar or shank 4 presses directly against the front follower and transmits the bumping shock through the springs 10.

The improved safety or auxiliary draft device described may also be employed and so arranged as to be drawn into action under extreme movements of the draft bar, even when the draft yoke or stirrup is intact and applied and operatively connected to the said draft bar. With this improved arrangement of draft rigging, means is always afforded for taking the car to its destination. If the yoke is broken, the auxiliary connection is operative; and if, for instance, the key of the auxiliary connection 105 110

should be broken, the yoke and other connections will be operative for the above purpose.

By arranging the parts so that the followers come together at the same time that the cross key 13 engages an extremity of the slot 12, the strains will be divided equally between the said key and the rivets 6 of the yoke 5.

10. What we claim is:

1. In a draft rigging, the combination with spring pressed followers, coöperating draft lugs and a draft bar having a yoke embracing said followers said yoke being secured to the draft bar, of slotted arms located on opposite sides of said draft bar and connected to the outer follower, and projections on said draft bar working with play within the slots of said arms, substantially as described.

2. In a railway draft rigging in combina-

tion a draw bar, a yoke secured thereto, a draft gear, a key and followers—the front follower being provided with forwardly extended arms, said arms being keyed to the 25 draw bar and being slotted to permit forward movement of the draw bar relative to the front follower.

3. In a draft rigging—in combination; a draw bar, a yoke secured thereto, a compression resisting member, a key and followers, the front follower being provided with forwardly extended slotted arms, the key passing through said arms and loosely engaging the same to the draw bar.

In testimony whereof we affix our signatures in presence of two witnesses.

GEORGE H. GILMAN.
HENRY M. ROBERTSON.
